UNITED STATES PATENT OFFICE.

GEORGE T. FIELDING, JR., OF NEW YORK, N. Y.

SWITCH FOR PROGRESSIVE LIGHTING.

1,024,251.

Specification of Letters Patent.

Patented Apr. 23, 1912.

Application filed February 28, 1911. Serial No. 611,368.

To all whom it may concern:

Be it known that I, GEORGE T. FIELDING, Jr., a citizen of the United States, and a resident of the city of New York, borough 5 of Manhattan, in the county and State of New York, have invented a new and Improved Switch for Progressive Lighting, of which the following is a full, clear, and exact description.

10 The invention relates to electric signs and similar display devices, and its object is to provide a new and improved switch for progressive lighting device, in which the electric lamps forming a predetermined design, 15 are progressively lighted to heighten the effect. For the purpose mentioned, use is made of a series of electric lamps and a switch for each of the said lamps, controlled by the current of the preceding electric 20 switch, so that after one lamp is lighted the next following one is automatically lighted at a predetermined interval, and so on, throughout the entire series of lamps.

A practical embodiment of the invention 25 is represented in the accompanying drawings forming a part of this specification, in which similar characters of reference indicate corresponding parts in all the views.

Figure 1 is a diagrammatic view of the 30 electric progressive lighting device; Fig. 2 is an enlarged side elevation of the switch on one of the lamps; and Fig. 3 is an enlarged cross section of the same.

The wires A and A' of a main electric 35 circuit are connected with a suitable source of electrical energy, and the said wires are provided with a main switch B, preferably of the rotary kind, for periodically opening and closing the main circuit. A series of 40 electric lamps C, C', C² are connected by wires D, D', D² with the wire A of the main circuit, and a wire D³ connects the first electric lamp C with a solenoid F, which in turn is connected by means of a wire D⁴ 45 with the wire A' of the main circuit, so that when the main circuit is closed by the main switch B then the first electric lamp C is lighted. The remaining lamps C', C² of the series are successively lighted, and for 50 this purpose use is made of switches E', E², respectively. The switches E, E' and E² are preferably in the form of solenoid switches. The core F² of the coil F is connected by a wire F⁴ with the coil G of the switch E', and which coil is provided with a fixed core 55 G' and a movable core G², of which the fixed core G' is connected by a wire G³ with the main circuit wire A' while the movable core G² is connected by a wire G⁴ with the coil H of the switch E². The coil H is provided with a fixed core H' and a movable core H², of which the fixed core H' is connected by a wire H³ with the main circuit wire A', while the movable core H² is connected by a wire H⁴ with the next following 60 switch.

The switches E, E', E² are alike in construction and a description of one will suffice for all. Each is mounted in a housing I fastened by a clamp J to the lamp, and 65 in the lower portion of the housing I is arranged the coil G, connected with the electric lamp at one end by a wire K and at the other end by the wire G⁴, with the movable cores G². The coil G is wound on 70 a tube L of an insulating material fixed to heads L', L² secured to the housing I, and in the head I² is adjustably mounted the fixed core G', preferably in the form of a screw, as plainly indicated in Figs. 2 and 75 3. The movable core G² extends into the upper portion of the tube L and is normally spaced from the inner end of the fixed core G', and the movable core G² is preferably 80 provided with a plunger N slideable in a cylinder O arranged in the upper portion of the housing I between the head L' and a head L³ in the top of the housing I. The cylinder O is provided with a binding post 85 P extending through the head L³ and connected with the wire G⁴. A spring Q is coiled on the movable plunger G² and rests with its lower end on the bottom cylinder O, while the upper end presses against the 90 under side of the plunger N so as to normally hold the movable core G² in uppermost position with the lower end of the core spaced from the fixed core G'. The lower end of the core G² is preferably 95 provided with a spring G⁵ adapted to engage 100 a contact point G⁶ that is on the upper end of the fixed core G'. Now it is evident that when the coil G is energized then the core G² is caused to slide downward against the tension of its spring Q and until the spring G⁵ on the end of the core G² finally makes contact with the core G' to close the circuit for the next following lamp, to light this lamp. When this takes place, the coil of 105 the next following lamp is energized and 110

the movable core therein is caused to make contact with the corresponding fixed core so that the next following lamp is lighted, and so on, throughout the entire series. At 5 the time the several lamps of the series are lighted the main switch B opens the main circuit so that the lamps in the whole series are suddenly extinguished, and when the main switch B again closes the main circuit 10 A then the lamp C is first lighted, and then successively the lamps C', C'', and so on, throughout the entire series, as previously explained. It is understood that when the main switch B opens the circuit, the coils 15 F, G, H are deenergized and consequently the cores F'', G'', H'' are returned to normal uppermost position by the corresponding springs Q. By having a plunger N connected with a movable core F'', G'', H'' it is 20 evident that the action of the movable core G'' is retarded when making contact with the fixed core G', so that the lamps C, C', C'' are lighted at desired intervals, which intervals can be changed by making the 25 plungers N to fit more or less tightly in the cylinders O.

Having thus described my invention, I claim as new and desire to secure by Letters Patent:

- 30 1. In a switch for progressive lighting, a cylindrical housing provided with a conducting head at one end and an insulating head at the opposite end, a tube disposed centrally of said housing, a coil wound 35 around said central tube, a cylinder within said housing, a permanent core carried by said conducting head and arranged to extend within the central tube, a movable core having a coil spring at one end and being 40 provided at the other end with a plunger, said plunger being disposed within said cylinder, and a spiral spring surrounding said movable core, one end of said spiral spring bearing on said plunger and the

opposite end bearing on the end of the cylinder. 45

2. In a switch for progressive lighting, a cylindrical housing provided with a conducting head at one end and an insulating head at the opposite end, a tube disposed centrally of said housing, a coil wound around said central tube, a cylinder within said housing, a permanent core carried by said conducting head and arranged to extend within the central tube, means for permitting the adjustment of the position of the permanent core, a movable core having a coil spring at one end arranged to engage said permanent core and being provided at the other end with a plunger, said plunger being disposed within the cylinder, and means for normally holding said movable core away from said permanent core. 55 60

3. In a switch for progressive lighting, a cylindrical housing provided with a conducting head at one end and an insulating head at the opposite end, a tube disposed centrally of said housing, a coil wound around said central tube, a cylinder within said housing, a permanent core carried by 70 said conducting head and arranged to extend within the central tube, a movable core having a resilient conductor at one end and being provided at the other end with a plunger, said plunger being disposed within 75 said cylinder, means arranged to engage the plunger for normally keeping said movable core away from said permanent core, and means permitting the adjustment of the position of said permanent core with 80 respect to the movable core.

In testimony whereof I have signed my name to this specification in the presence of two subscribing witnesses.

GEORGE T. FIELDING, JR.
